PRESSURE COOKER

Lawrence L. Ludington, Muncie, Ind., assignor
to Ball Brothers Company, Muncie, Ind., a cor-
poration of Indiana

Application November 3, 1934, Serial No. 751,271

3 Claims. (Cl. 220—61)

The object of my invention is to provide an improved closure for cooking utensils of that type commonly referred to as "pressure" cookers, of such character as to be readily handled and manipulated by the average housewife, without danger of being burned, and of such character that a pressure tight relation with the containing vessel may be readily established and as readily disestablished.

The accompanying drawing illustrates my invention.

Fig. 1 is a plan of my improved closure;

Fig. 2 a side elevation, in partial vertical section, of a cooking utensil equipped with my improved closure;

Fig. 3 a diametrical section of the primary ring;

Fig. 4 a fragmentary side elevation of the upper end of the container;

Fig. 5 a fragmentary radial section, about full size, and

Fig. 6 a section on line 6—6 of Fig. 5.

In the drawing 10 indicates a receptacle provided at its upper open end with an external circumferential flange 11 and a circumferential series of outwardly-projecting circumferentially-spaced anchor lugs 12. The upper end of the circumferential wall of receptacle 10 is provided with a pocket 13 at the inner edge of which is a circular upwardly-presented ridge 14 the upper surface of which is accurately machined and preferably slightly rounded as indicated at 15 (Fig. 7).

My improved closure comprises a primary ring R, a secondary ring R' and a sheet metal cover C.

The primary ring R comprises a radial flange 20 having diametrically opposed ears 21 each perforated at 22, and a skirt flange 23 provided at its lower end with a circumferential series of circumferentially-spaced inwardly-projecting anchor lugs 24 adapted to mate with the anchor lugs 12. Journalized in each perforation 22 is a shaft 25 provided at its lower end with a pinion 26 and at its upper end with an operating handle 27. The skirt flange 23 of ring R is threaded at 28.

Ring R' is provided with external threads 30 mating with threads 29 of ring R and is also provided with a circumferential series of internal gear teeth 31 meshing with the teeth of pinions 26. Ring R' at its lower end is provided with a downwardly-projecting circular ridge 32.

The cover C, preferably formed of sheet metal of comparatively light gauge is conveniently circular in plan, the pocket 13 being annular. This

cover is preferably upwardly-domed at its center, as indicated at 33 and is provided with a depending skirt 34 which is provided at its lower end with an inwardly-projecting flange 35 axially spaced from the surmounting portion of the cover. Preferably the spacing of flange 35 from the surmounting portion of the cover should be a little more than the thickness of an average index finger of a human hand in order to facilitate cleaning, and the gauge of that portion of the cover forming the flange 35, skirt 34 and the cover portion surmounting flange 35 should be such that flange 35 will be axially flexible.

The operation is as follows:

Cover C being placed in position with its flange 35 resting upon rib 14, and ring R' being threaded into ring R to space rib 32 from the upper ends of anchor lugs 24 a distance slightly greater than the distance from the upper surface of that portion of cover C adjacent its perimeter and the lower ends of anchor lugs 12, the assembled ring structure is laid upon cover C, anchor lugs 24 passing downwardly between anchor lugs 12. Ring R is then rotated to bring anchor lugs 24 beneath anchor lugs 12, this rotative movement being preferably limited by a stop pin 40 (Fig. 4) so positioned, as indicated in Fig. 4, that rotation of ring R in one direction to contact a lug 24 with pin 40 will position lugs 24 beneath lugs 12, while rotation in the opposite direction will position the lugs properly to permit axial separation of the ring structure from the container. Thereupon, pinions 26 are rotated, by manipulation of handles 27, to cause the primary ring R to move upwardly to bring the upper ends of lugs 24 into engagement with the lower ends of lugs 12, thereby pressing flange 35 upon rib 14.

Upon the accumulation of vapor pressure within the container, said pressure acting equally in opposite directions relatively upon the upper face of flange 35 and the under face of that portion of the cover surmounting said flange, insures a pressure-tight seating of flange 35 upon rib 14. The said vapor pressure acting upon the central portion of the cover cantilevers, the perimeter of the cover upon rib 32 to further assist in insuring a tight seating of flange 35 upon rib 14. As a consequence it is not necessary for the operator in manipulating handles 27 to seat the anchor lugs 24 very tightly against the anchor lugs 12.

After the cooking operation has been performed reverse manipulation of handles 27 will turn ring R' within ring R; rib 32 sliding upon 55

cover C, until the frictional resistance between lugs 24 and lugs 12 is eliminated, whereupon further manipulation of handles 27 in reverse direction will cause ring R to turn upon ring R', the 5 frictional resistance between the threads 29 and 30 being less than the frictional resistance of rib 32 upon cover C, so that lugs 24 will be swung from beneath lugs 12 until one of the lugs 24 contacts with stop pin 40 at which time the lugs 10 24 are in such positive relation to lugs 12 that the ring structure RR' may be lifted from the standard 10.

For economy in fabrication pocket 13 and rib 15 should be circular and the upper faces of lugs 15 24 should be all in the same plane and the lower faces of lugs 12 should likewise be in one plane. This is possible because rotation of ring R relative to container 10 is not depended upon to exert any clamping action upon the cover C. 20 Cover C will be equipped with the usual handle 45, safety valve 46 and temperature or pressure indicator 47 which form a part of my present invention.

If stop pin 40 is so placed that counter-clockwise movement of ring R will move lugs 24 beneath lugs 12, threads 29 and 30 should be right-hand threads, and shafts 25 will be turned clockwise to clamp the cover in place.

I claim as my invention:
30 1. The combination with a container having a cover seat at its open end and anchor lugs, a

cover mating with said seat, and a removable cover retainer comprising, (1) a primary ring having anchor lugs mateable with the anchor lugs of the container and a threaded portion, and (2) a secondary ring having threads mating with the aforesaid threads, an annular series of gear teeth, and a portion restable upon the cover, a shaft journaled in the primary ring, a pinion carried by said shaft and meshing with said annular series of gear teeth and a manipulating handle carried by said shaft.

2. The combination with a container having a cover seat at its open end and anchor lugs, a cover mating with said seat, and a removable cover retainer comprising, (1) a primary ring having anchor lugs mateable with the anchor lugs of the container, and a threaded portion, and (2) a secondary ring having threads mating with the aforesaid threads and a portion restable upon the cover. 20

3. The combination with a container having a cover seat at its open end and anchor lugs, a cover mating with said seat, and a removable cover retainer comprising, (1) a primary ring having anchor lugs mateable with the anchor lugs of the container, and a threaded portion, and (2) a secondary ring having threads mating with the aforesaid threads and a portion restable upon the cover, and means operative between the two rings to cause relative angular movement thereof. 30
